UNITED STATES PATENT OFFICE.

HENRY JACOB BAXTER, OF EMERALD, WISCONSIN.

HORSE-HITCHER.

SPECIFICATION forming part of Letters Patent No. 439,463, dated October 28, 1890.

Application filed March 28, 1890. Serial No. 345,748. (No model.)

To all whom it may concern:

Be it known that I, HENRY JACOB BAXTER, a citizen of the United States, residing at Emerald, in the county of St. Croix and State of Wisconsin, have invented certain new and useful Improvements in Horse-Hitchers; and I do hereby declare the following to be a full, clear, and exact description of the invention, such as will enable others skilled in the art 5 to which it appertains to make and use the same.

This invention relates to fasteners, and is especially designed to provide means for quickly and securely hitching a horse in any 15 required position, whether to a manger or post.

The improvement consists of a plate provided with converging jaws and a wedge-shaped block which is adapted to be inserted 20 between the said jaws and clamp the strap, rope, or cord between its sides and the opposing sides of the said jaws, as will hereinafter more fully appear.

The improvement further consists of the 25 novel features which hereinafter will be more fully described and claimed, and which are shown in the annexed drawings, in which—

Figure 1 is a top plan view of a fastener embodying my invention. Fig. 2 is a front 30 view of the fastener. Fig. 3 is a section on the line X X of Fig. 1.

The plate A is provided with the converging jaws B B, which have retaining-lugs a a at their upper edges, which are designed to 35 project over the top of the wedge-block C and hold the latter to the plate, and also extend over the strap and prevent it slipping from the fastener. These jaws flare at their front ends, so as not to present any sharp angles 40 to injure the strap. The wedge-block C, rounded at its rear end, is provided with the extension D at its upper rear corner or end for a twofold purpose—to present a thumb-grip and a shoulder or stop to prevent the 45 strap, rope, or cord from slipping off the said block.

The operation of the fastener is as follows: The rope, strap, or cord is passed around the block and the latter is pressed forward be- 50 tween the jaws B B, thereby clamping the said strap, rope, or cord between the sides of the wedge and the opposing sides of the jaws. To prevent the wedge-block C from getting lost, it is provided with a shank E, which

projects through a slot e in the plate, being 55 held to said plate by pin F, which passes through the said shank. The plate A is strengthened by plate A', which is projected from the rear edge of the said plate. The plates A and A' and the jaws B B are cast 60 in one piece for cheapness and stability.

Having thus described my invention, what I claim, and desire to secure by Letters Patent, is—

1. The combination, with the plate having 65 converging jaws, of the wedge-block adapted to be inserted between the said jaws and clamp a rope, strap, or cord between its sides and the opposing sides of the said jaws.

2. The combination, with the plate having 70 converging jaws and having retaining-lugs at the upper edge of the said jaws, of the wedge-block adapted to be inserted between the jaws, substantially as and for the purpose described.

3. The combination, with the plate having 75 converging jaws, of the wedge-block to be inserted between the jaws and having a projection which extends beyond the rear end of the block and above the top edges of the jaws, 80 substantially as described, for the purpose specified.

4. The combination of the plate having converging jaws and retaining-lugs at the upper edges of the said jaws and the wedge-block 85 having a rear extension, substantially as described.

5. The combination, with the plate having 90 converging jaws and having a slot between the jaws, of the wedge-block having a shank 95 which extends through the said slot, and a pin passing through the said shank, substantially as set forth.

6. The herein-described fastener, composed 95 of the plates A and A', which are disposed at right angles to one another, the plate A having converging jaws and retaining-lugs at the upper edges of the said jaws, and having slot e, and of the wedge-block having extension D and shank E, the latter extending 100 through slot e and held in place by pin F, which passes through the said shank.

In testimony whereof I affix my signature in presence of two witnesses.

HENRY JACOB BAXTER.
